UNITED STATES PATENT OFFICE.

EDWARD MAY MUNRO, OF LONDON, ENGLAND, ASSIGNOR OF ONE-HALF TO THE
R. E. T. CONSTRUCTION COMPANY LIMITED, OF LONDON, ENGLAND.

SOCKET OR BASE OF TROLLEY-POLES FOR ELECTRIC TRACTION SYSTEMS.

1,100,680.

Specification of Letters Patent. Patented June 16, 1914.

Application filed February 17, 1913. Serial No. 748,948.

To all whom it may concern:

Be it known that I, EDWARD MAY MUNRO, subject of the King of England, residing at London, in England, have invented certain 5 new and useful Improvements in the Sockets or Bases of Trolley-Poles for Electric Traction Systems, of which the following is a specification.

This invention relates to the sockets or 10 bases of trolley-poles for electric traction systems and has particular reference to systems in which railless vehicles deriving their power from overhead conductors are employed. In such a system it is important 15 to allow the vehicle to vary its position relatively to the conductors without danger of disengaging the contact shoes or other collectors and to prevent undue side strain being set up between the conductor and the 20 collector. According to this invention the position of the rotatable portion of the socket is controlled by a cam or inclined surface acting in conjunction with a friction roller or the like. The cam may be pressed 25 into contact with the roller either by the weight of the trolley-arm and head or by the action of a spring.

In one convenient construction the standard or base is provided with a fixed sleeve 30 or tubular member provided at its upper end with two friction rollers mounted in suitable lugs. Upon these rollers rests the rotatable head carrying the usual pole-socket pivoted to it. The lower portion of 35 the rotatable head which is in contact with the rollers is formed as a double cam having the two deepest portions of its surface so disposed relatively to the head that the head is in its highest position when the 40 trolley-arm or pole is parallel with the longitudinal axis of the vehicle. These two portions of the cam surface may be flat for a small length so as to allow of slight rotary motion without the control coming into 45 operation but when the vehicle turns out and causes the trolley-arm to lie at more than a slight angle with the car the inclined portions of the cam are brought into coöperation with the rollers and the weight of 50 the head and the trolley-arm tends to rotate the socket further in the same direction.

In the accompanying drawings:—Figure 1 is a vertical central section through one construction of a socket or base according 55 to this invention. Fig. 2 is a side elevation,

partly in section, taken at right angles to Fig. 1. Fig. 3 is a transverse section through the roof of a vehicle upon which two sockets, according to this invention, are mounted, and, Figs. 4 and 5 are plans of two 60 frames or holding members used in the mounting of the sockets as shown in Fig. 3.

Like letters indicate like parts throughout the drawings.

With reference first to Figs. 1 and 2, A is 65 a tubular socket provided at its upper extremity with friction rollers B supported in lugs A'. On these friction rollers rest inclined or cam surfaces C' formed on a rotatable head C. This head C is fitted with 70 a tubular stem D which extends down within the tube or socket A, roller bearings being provided at E and E' so that the stem D may rotate and move up and down within the tube A. A spring F, in compression, is placed between a channel or ball-race E² adjustably secured to the bottom of the stem D and a fixed internal collar G within the tube A. This spring therefore tends to keep the cam surfaces C' pressed 75 down in contact with the friction rollers B. Within the tubular stem D is a spring 80 H acting between a fixed internal collar H' and the lower end of a central rod or tie J. The upper extremity of this rod engages 85 with the hooked end of a socket K which receives the lower end of the trolley-arm K'. This rod J, spring H and socket K are of the usual construction, the function of the spring H being to keep the upper extremity of the trolley-arm K' raised so that the collector is brought into contact with the overhead conductor. Attached to the 90 rotatable head C is a light cover or petticoat L which serves to protect the cam surfaces 95 and friction rollers from the weather.

As shown in Figs. 1 and 2 the deepest portions of the cam surfaces C' are resting upon the friction rollers B, this being the normal position when the axis of the trolley-arm K' lies parallel with the longitudinal center line of the vehicle, as when the vehicle is running directly beneath the overhead conductor. Should the vehicle turn out from this position the head C is rotated 100 and the inclined cam surfaces C' are brought into engagement with the friction rollers and tend to rotate the head C and the trolley-arm K' still farther in the direction in which they have moved. That is to say, the 105 110

head, owing to the action of the cam surfaces, is turned in such a direction as to lessen or prevent side strain between the overhead conductor and the collector.

- 5 Fig. 3 illustrates diagrammatically one method of mounting two sockets, according to this invention, on the roof of an electrically propelled vehicle. A spectacle frame or casting, part of which is shown separately 10 in Fig. 4, is formed with two flanged rings M which receive the tubes A. This spectacle frame extends across the vehicle beneath the roof timbers N and is supported by vertical 15 channel irons P. Near the bottom of the tubes A a bodice R is provided, bolted or riveted at each end to the channel irons P, and formed so as to encircle and hold the tubes A. This bodice R is shown separately in plan in Fig. 5.
- 20 The improved construction of trolley-socket or base is simple and not likely to get out of order and further it can be made very low so that it occupies little space on the roof of the vehicle. Another advantage is 25 that very little lateral space is required.

What I claim as my invention and desire to secure by Letters Patent is:—

1. A socket or base for the trolley-pole of an electrically propelled vehicle comprising 30 a rotatable head, a relatively stationary supporting member, and inclined or cam surfaces acting to control the motion of the rotatable head in the manner described to 35 counteract lateral pressure on the conductor when the vehicle is not running directly beneath the conductor.

2. A socket or base for the trolley-pole of an electrically propelled vehicle comprising 40 a rotatable head having inclined or cam surfaces, a stationary supporting member and friction rollers mounted thereon to coöperate with the cam surfaces to control the motion of the head in the manner described.

3. A base for the trolley-pole of an electrically propelled vehicle comprising 45 a tubular socket, friction rollers mounted on the upper part of such socket, a head rotatable relatively to the socket and provided with inclined or cam surfaces coöoperating with 50 the friction rollers, and a spring acting to keep the cam surfaces in contact with the friction rollers.

4. A trolley pole support for an electrically propelled vehicle, a spectacle frame, 55 and two rotatable sockets or bases for trol-

ley-poles each socket or base being provided with inclined or cam surfaces and friction rollers as and for the purpose described.

5. A base for the trolley-pole of an electrically propelled vehicle comprising a tubular socket, friction rollers mounted on the upper part of such socket, a head co-axial with said socket and rotatable relatively thereto, cam surfaces formed on the underside of such head and disposed so as to rest 60 upon the friction rollers and a tubular stem attached to the rotatable head and extending 65 down within the tubular socket.

6. A base for the trolley-pole of an electrically propelled vehicle, comprising a tubular socket, friction rollers mounted on the upper part of such socket, a head co-axial with said socket and rotatable relatively thereto, cam surfaces formed on the underside of such head and disposed so as to rest 70 upon the friction rollers, a tubular stem attached to the rotatable head and extending down within the tubular socket and a spring 75 acting between the tubular stem and the tubular socket to keep the cam surfaces in 80 operative connection with the friction rollers.

7. A base for the trolley-pole of an electrically propelled vehicle, comprising a tubular socket, friction rollers mounted on the upper part of such socket, a head co-axial 85 with said socket and rotatable relatively thereto, cam surfaces formed on the underside of such head and disposed so as to rest upon the friction rollers, a tubular stem attached to the rotatable head and extending 90 down within the tubular socket, a spring acting between the tubular stem and the tubular socket to keep the cam surfaces in operative connection with the friction rollers, a pole-socket pivotally mounted on the rotatable head, a rod attached to the inner end of the pole-socket and extending down within the tubular stem, a fixed collar within the tubular stem and a spring acting between 95 the fixed collar and the lower extremity of the rod and tending to keep the outer end of the pole-socket raised.

In testimony whereof I have signed my name to this specification in the presence of two subscribing witnesses.

EDWARD MAY MUNRO.
